Attorney.

UNITED STATES PATENT OFFICE

TILLMAN CAHN, OF ELMINS PARK, PENNSYLVANIA, ASSIGNOR TO PIONEER SUSPENDER COMPANY, A CORPORATION OF PENNSYLVANIA

DESIGN FOR SUSPENDERS

Application filed January 6, 1932. Serial No. 42,378. Term of patent 14 years.

To all whom it may concern:

Be it known that I, TILLMAN CAHN, a citizen of the United States, residing at Elkins Park, in the county of Montgomery State of Pennsylvania, have invented a new, original, and ornamental Design for Suspender, of which the following is a specification, reference being had to the accompanying drawing, forming part thereof.

The figure is a view in perspective of a suspender embodying the design.

The following comprises the distinguishing features of the design: The pad at the

junction of the shoulder straps and back strap is of triangular form with one corner directed downwardly. The three pads connecting the suspender ends to the shoulder straps and back straps, all carry the triangular suggestion with one corner of each downwardly directed, so that there is created a harmony in the combined aspect of all the pads.

I claim:—

The ornamental design for a suspender as shown and described.

TILLMAN CAHN,
